CARBURETOR

Maldwyn E. Jones, Ferguson, Mo., assignor to
 Carter Carburetor Corporation, St. Louis, Mo.,
 a corporation of Delaware

Application June 30, 1943, Serial No. 492,954

6 Claims. (Cl. 261—41)

This invention relates to carburetors for internal combustion engines and consists particularly in novel means for insuring the delivery of fuel and air in proper proportions under varying load conditions and positions of the throttle.

The use of an air bled main nozzle in a carburetor has the advantage that it facilitates the lifting of fuel under lowest suction conditions and also tends to lean out the mixture when the carburetor is operating at a high speed with substantially opened throttle. In other words, the fuel mixture proportion curve of such a carburetor, with the throttle in wide open position, is desirably rich at the inner or low suction end and tends to drop toward the outer or high speed end.

However, the air bleed has certain disadvantages in connection with the fuel supply under part throttle conditions. One such disadvantage is that where the main metering jet is reduced by a metering valve, as is the usual case under part throttle conditions, the air and fuel tend to emerge from the main nozzle in spurts and this is reflected in the uneven running of the engine known as "surging." Furthermore, the part throttle mixture curve should remain substantially constant throughout the economy range operation of the engine, but if the nozzle is air bled, the part throttle curve tends to become leaner as the speed increases at an even greater rate than the full throttle curve of an air bled nozzle. The excessive leaning effect at the outer end of the part throttle curve can be partially corrected by the use of a properly shaped metering valve, but a valve having a plurality of different steps or tapers is undesirable where the valve is controlled by a suction responsive device, particularly a diaphragm, because of the somewhat erratic movement of the diaphragm under varying suction conditions. Because of this erratic response of the diaphragm, it is desirable that the metering valve apply a constant restriction to the fuel supply throughout the part throttle range so that the erratic hunting of the diaphragm cannot adversely affect the normal metering of the fuel by suction applied to the main nozzle under the influence of varying engine suction. When the carburetor suction drops to or below approximately three inches of mercury, as when the throttle valve is substantially wide open, a smaller portion thereof should enter the metering orifice to provide for a richer, power mixture.

An object of the present invention is to provide a carburetor having the advantages of an air bled main nozzle throughout the full throttle or

power range of operation, while eliminating the disadvantages of the air bleed in the part throttle or economy range.

5 A more detailed object is to provide a main nozzle air bleed which is effective only during the full throttle or power range operation.

10 Another detailed object is to provide an idling system fed from the main nozzle passage in such a way that all fuel cannot be swept out of the 15 idling system because of the superior suction in the main nozzle passage.

These objects and other objects hereafter appearing are attained substantially by the structure illustrated in the accompanying drawing in 15 which:

Fig. 1 is a top view of a carburetor having the invention applied thereto.

Fig. 2 is a side view partly in section better illustrating the invention.

20 Fig. 3 shows mixture quality curves graphically illustrating the advantages of the invention.

The carburetor shown has a downdraft mixture conduit or barrel including an air inlet horn 10 at the upper extremity, the passage of air through 25 which is controlled by a butterfly choker valve 11. At the lower or outlet end of the barrel there is provided a butterfly throttle valve 12 for controlling the discharge of mixture from the carburetor. Between the two valves there are provided 30 the venturis 13 forming part of the mixing chamber. A fuel bowl 14 is formed adjacent the barrel and contains a float 15 controlling needle valve 16 for maintaining the fuel at a substantially constant level. In the lower part of the 35 fuel bowl there is provided a main metering orifice element 17 through which gasoline is supplied to upwardly extending fuel passage 18 and main nozzle 19 discharging into the smallest or primary venturi 13. Fuel is also supplied to a cross passage 20 which is intersected by a second vertical 40 passage 21 communicating with a cross passage 22 above the fuel level and downwardly extending passage 23 opening into the mixture conduit through an idling port 24 located adjacent the edge of the throttle valve when closed. Vertical 45 passage 24 extends below passage 20 to form a well, as at 25, which is below the fuel level and, consequently, always filled with fuel. An idle metering tube 26 is mounted in passage 21 and extends downwardly past cross passage 20 into well 25.

A casing member 30 is attached to the outer wall of the fuel chamber for securing a diaphragm 31 in position. The space to the right hand side of the diaphragm forms a suction chamber which

is connected by a passage 32 to the mixture conduit posterior to throttle 24. The diaphragm is gripped between a pair of cup washers 33 and 34, the latter forming a stop for abutting casing member 30 to limit the rightward movement of the diaphragm. The diaphragm is constantly urged to the left against the effect of suction by a coiled spring 35. An actuator stem 36 extends through and is secured to the diaphragm. This stem projects adjacent a pivoted lever 37 which is connected by a link 38 to throttle lever 39. Lever 39 has a perforation 40 for attachment of a link extending to the usual accelerator pedal located in the driver's compartment.

A metering pin 45 is connected to and extends leftwardly of plunger rod 36 and has an intermediate stepped portion 46 extending through and restricting the effective opening in metering orifice element 17. Pin 45 extends into lower cross fuel passage 20 and past idling jet tube 26 which is mounted off center of passage 20 to permit this.

Extending upwardly from the left hand extremity of cross passage 20 is an upwardly extending air bleed passage 48 which communicates with the atmosphere above the fuel bowl through a restriction 49. Passage 20 adjacent its intersection with air passage 48 is shouldered to form a valve seat normally receiving a disk valve 50 urged toward this seat by a coiled spring 51 compressed between the disk valve and a threaded plug 52 secured in and sealing the end of passage 20. An actuating pintle 53 projects rightwardly from disk valve 50.

In operation, with the throttle valve in idling position, diaphragm 31 is held in its right hand position, as shown, against spring 35, by the engine suction. As the throttle valve is opened, lever 37 is rotated clockwise so as to push rod 36 and the diaphragm to the left and, in turn, move metering portion 46 of the metering pin through the metering orifice element. Until the throttle valve arrives at a substantially open position, between three-fourths and full open, a straight or cylindrical portion of the metering pin is positioned in the metering orifice so that the effective size thereof is not varied. However, as the throttle is farther opened, the smaller step of the metering pin enters the orifice to provide for a richer, power mixture. Substantially at the same time as the power step of the metering pin enters the orifice, the left hand extremity of the pin engages pintle 53 and unseats disk valve 50 so as to open air bleed passage 48. Thereafter, air enters the fuel stream in main fuel passage 18 and nozzle 19, whereas in the part throttle range, the main nozzle discharges "solid" fuel, no air being admitted.

In case the load on the engine and, consequently, its speed, is varied for a fixed setting of the part throttle valve, diaphragm 31 can respond independently of the throttle linkage to vary the position of the metering pin and, if the suction drops low enough, to open air bleed valve disk 50.

The mixture quality or proportion curve shown in Fig. 3 graphically illustrates the advantages of the invention. These curves represent proportions of air to fuel in the mixture supplied as the rate of air flow increases. The curve A is the part throttle curve of an air bleed main nozzle carburetor and becomes excessively lean at the outer end. The curve B is obtained for full throttle operation with an air bleed main nozzle. While the curve A is undesirably lean at the outer end, curve B is satisfactory, exhibiting a firm, relatively

rich inner end portion, as at 70, and descending intermediate and outer end portions. The curve C illustrates the operation of the carburetor in the part throttle range with a "solid" fuel main nozzle, while the curve D shows the functioning of the same type of nozzle in the full throttle range. The curve C is satisfactorily flat and regular in its intermediate portion, but the curve D is relatively weak or lean at its inner end portion and ascends outwardly to indicate increasing richness.

By the use of the invention, the carburetor delivers fuel of the proportions represented by the curve C during the part throttle range and by the curve B in the full throttle range. The positions of the curves on the flow sheets can, of course, be adjusted by means of the various fixed fuel and air orifices and the metering pin, the valve 50 and the step on the metering pin serving to insure the proper shaping of the curves.

While the invention has important advantages when used in connection with a metering device controlled by a suction diaphragm, the principles thereof may also be used to advantage with other metering arrangements, such as where the metering valve is controlled by a piston or, even manually, or where a separate step-up or economizer device is used.

The invention may be modified in these and other respects as will occur to those skilled in the art without departing from the spirit thereof and the exclusive use of all modifications as come within the scope of the appended claims is contemplated.

I claim:

1. In a carburetor, a mixture conduit having a venturi, a throttle in said conduit, a main fuel passage discharging into said venturi and having a metering orifice element, an economizer valve controlling said element, an air bleed duct opening into said fuel passage, a normally closed valve controlling said duct, and means responsive to movement of said throttle to a substantially wide open position for opening said duct valve.

2. In a carburetor, a mixture conduit having a venturi, a throttle in said conduit, an idle passage for feeding fuel to a port in the wall of said conduit adjacent the edge of said throttle when closed, a main fuel passage discharging into said venturi and having a metering orifice element, an economizer valve controlling said element, air bleed means opening into said main fuel passage, a valve controlling said bleed means, and means responsive to relatively low suction in said conduit posterior to said throttle for opening said bleed means whereby said passage supplies solid fuel in the high suction range and a mixture of fuel and air in the low suction range.

3. In a carburetor, a mixture conduit having a venturi and a throttle therein, a main fuel passage discharging into said venturi and having a metering orifice element, air bleed means opening into said fuel passage below the normal level therein, an economizer valve controlling said orifice and having lean and rich positions, a valve for closing said bleed means, a suction operated device, and operative connections between said device and said valves constructed and arranged to move said economizer valve to its rich position and to open said bleed valve responsive to relatively low suction in said conduit posterior to said throttle.

4. In a carburetor, a mixture conduit having a throttle and a venturi therein, a main fuel passage discharging into said venturi and having a

metering orifice element, an air bleed duct opening into said fuel passage, an economizer valve controlling said orifice and having lean and rich positions, a valve controlling said duct and positioned to be actuated by said economizer valve, and an operative connection between said throttle and said economizer valve constructed and arranged for moving said economizer valve to its rich position and opening said duct valve when said throttle is substantially fully opened.

5. In a carburetor, a mixture conduit, a throttle therein, a main fuel passage discharging into said conduit and having a metering orifice element, air bleed means opening into said passage, a normally closed first valve controlling said bleed means, a second valve controlling said metering orifice element, an economizer device, and operative connections between said device and said valves for opening said first valve and moving said

second valve to its rich position when the carburetor is operating in the power range.

6. In a carburetor, a mixture conduit having a throttle therein, a main fuel passage discharging into said conduit and having a metering orifice element, air bleed means opening into said fuel passage below the normal level therein, a metering pin controlling said orifice and having lean and rich positions, a valve for closing said bleed means, and throttle operated means for actuating said metering valve to increase the richness of the mixture supplied by the carburetor, as said throttle is opened, said bleed valve being engageable by said pin when said throttle is moved to its substantially wide open position for opening said bleed valve to cause air to be entrained with the fuel discharged from said passage during full throttle operation.
